UNITED STATES PATENT OFFICE

2,026,738

SALT SHAKER OR THE LIKE

James W. Jennings, Providence, R. I.

Application December 20, 1934, Serial No. 758,453

1 Claim. (Cl. 65—45)

My invention relates to shakers or containers for dispensing salt and other condiments.

An object of my invention is to enable the utilization of the base of the shaker as a supporting element combined with inherent means for permitting the replenishment of the contents of the shaker body whereby the usual removable dispensing cap may be discarded if desired.

Another object is to protect the lower end of the frangible body of the container or shaker from fracture, regardless of the material of the base.

A further object is to enable the utilization of the economic and physical advantages of metal as a material for the base in this type of mounting without the well known disadvantage of corrosion heretofore incident to the use of metal in containers for saline contents.

Still further objects are to attain these ends in a simple and inexpensive structure.

Other objects and advantages will be herein-after adverted to.

To the above recited ends essentially my invention consists in such parts and in such combinations of parts as fall within the scope of the appended claims.

In the accompanying drawing,

Figures 1 and 2 are a plan view and a side elevation respectively of a shaker or dispensing container embodying my invention,

Figure 3, a plan view of the base, the body being detached, and

Figure 4, a section of the container taken on line 4—4 of Figure 2.

Like reference characters indicate like parts throughout the views.

My shaker includes a metallic base 1 comprising a body portion 8, circular and upwardly tapering or conical, terminating in an upright annular shoulder portion 10 continuous with and constituting a part of the wall of a central cavity 12 in the base portion 8, which wall is provided with an internal screw thread 13.

A disk 14 of cork, rubber, or other non-corrosive material is seated upon the floor of the cavity, and serves both for insulation from corrosion, and as a cushion for shock absorbing purposes.

The body member 16 of the container is composed of glass, porcelain, or other vitreous or frangible material. This member includes a hollow spherical head portion 17 and a tubular neck or shank portion 18; the latter being provided with an external thread 19 adapted to

engage the thread 13 in the cavity. In the top of the head 17 are dispensing perforations 21.

In order to charge the container the body 16 is manually unscrewed from the base 1 and salt or other condiment is poured by one hand into the head portion 17 through the neck portion 18, the other hand of the operator covering the perforations 21 during the charging step. Still retaining the head in his hand the operator uses his other hand to screw the base 1 upon the neck portion 18 until the end face of the latter abuts snugly against the disk 14. The container is now ready for use and the contents may be dispensed as desired through the perforations 21.

It will be noted that the disk 14 acts as a cushion or shock absorber when the container body is screwed with excessive force or abruptness into the base, or when the base contacts with a table too violently, and thus accidental fracture of the lower portion 18 of the frangible body 16 is prevented.

There is no possibility of corrosion inducing contact of the saline contents of the body 16 with the metallic base 1, since the threaded portion of the base contacts solely with the exterior of the portion 18 of the vitreous container body, and the flat end face of the body is insulated from the remainder of the base by the disk 14 and none of the saline contents of the body are permitted to escape into direct or indirect contact with any portion of the base.

By reason of the absence of corrosion afforded by the described construction, it is possible to utilize the superior advantages of a metallic base, namely the greater relative weight of the base, and the greater accuracy of forming the thread and cavity by mechanical construction, as well as the greater variety of materials available for contributing an artistic contrast between the base and body of the container.

While I have described a specific constructional embodiment of my invention, it is obvious that desired changes in the arrangement and the size of the parts and in their function and operation, may be made without departing from the spirit and the scope of the invention as defined in the appended claim.

I claim:—

A shaker comprising an imperforate metallic base having a tubular upstanding shoulder portion, said base having a relatively wide disk-like portion of appreciably greater diameter than the tubular shoulder portion with a narrow supporting flange at its periphery, said shoulder portion having a closed bottom, a flat relatively thin disk

of non-corrosive cushioning material seated upon said bottom and approximately covering the same from side to side, and a globular hollow body of frangible material having dispensing perforations in the top thereof, said body having a relatively small depending neck provided with interfitting engagement with the shoulder por-

tion and secured thereto, said neck having the lower end thereof seated upon the cushioning disk, said disk insulating the metallic base against corrosion and cushioning the frangible body portion against shock.

JAMES W. JENNINGS. 5
